UNITED STATES PATENT OFFICE.

OSWALD W. SCHUBERT, OF MILWAUKEE, WISCONSIN.

DESIGN FOR A DINNER-PLATE.

SPECIFICATION forming part of Design No. 30,561, dated April 18, 1899.

Application filed January 23, 1899. Serial No. 703,184. Term of patent 7 years.

To all whom it may concern.

Be it known that I, OSWALD W. SCHUBERT, a citizen of the United States, residing at Milwaukee, in the county of Milwaukee and State 5 of Wisconsin, have invented and produced a new and original Design for Dinner-Plates, of which the following is a specification, reference being had to the accompanying drawings, forming part thereof.

Figure 1 is a plan view of a dinner-plate, showing my new design. Fig. 2 is a sectional view taken on the line X X of Fig. 1.

As shown in the drawings, the leading or material feature of my design consists of a series of dished extensions A, joining the circular inner edge of the rim B, which surrounds

the plate, said rim being extended in a series of curves C, surrounding the extensions A, and the main body D of the plate and the circular extensions A being depressed below the 20 level of said rim, the inner edge E of the rim of the plate and of said extensions rising to a common level and being circular in outline.

Having thus described my invention, what I claim as new, and desire to secure by Letters 25 Patent, is—

The design for a dinner-plate, substantially as herein shown and described.

O. W. SCHUBERT.
